SCREEN AND CLEANING MEANS THEREFOR

John B. Goldsborough, Croton-on-Hudson, N. Y.

Application December 10, 1932, Serial No. 646,639

13 Claims. (Cl. 210—196)

This invention relates to the screening of sewage and the like, and more particularly to rotary screens, such as disc screens, and means for cleaning the screens.

5 An important object of the invention is to provide novel and advantageous forms of screens. Another important object of the invention is to provide novel and advantageous means for cleaning screens of the character to which reference has been made. A further object of the invention is to provide novel screens and novel cleaning means adapted to cooperate with each other. A still further object of the invention is to provide means for operating the screens and cleaning means in suitable coordinated relationship.

One feature of the invention involves the use of an inclined disc screen having substantially radially-arranged screening slots. Another feature of the invention relates to screen-cleaning means acting radially of the screen to clean said screening slots from the inner to the outer ends thereof. It is also a feature of the invention to have the cleaning means rotate with the screen about the axis of rotation of the latter while completing the cleaning action from the inner to the outer ends of certain of the substantially radial slots. A further feature of the invention relates to means whereby the cleaning means moves with the screen while cleaning a radial path thereon, is withdrawn therefrom, moved rearwardly to a position over another path on the screen, and moved into cooperative relation with the screen to start cleaning the last mentioned path. It is also a feature of the invention to provide a rotary screen having a drum portion with longitudinal screening slots, and screen-cleaning means travelling with the screen while acting from the upper to the lower ends of the slots in a longitudinal path off the screen, and then being shifted away from the screen and rearwardly to engage the screen in a path adjacent to the first and partially overlapping the same.

The invention also involves the feature of a rotary screen including a disc portion and a drum portion, preferably in the form of a frustum of a cone, having longitudinal screening slots. A further feature of the invention involves the use of such a screen with cleaning means acting along said screening slots. This cleaning means may also move with the rotating screen until a path thereon has been completely cleaned, and then be withdrawn from the screen and brought into engagement with another path to be cleaned. It is also a feature of the invention to provide a rotary screen including a disc portion with substantially radial slots and a drum portion having longitudinal slots so that cleaning of both parts may be cleaned by means acting along the slots whereby the screenings from the drum will be

deposited on the disc and then moved to the periphery of the disc and discharged.

A further feature of the invention relates to the use, with a rotary screen having a disc portion with radial screening slots and a drum portion with longitudinal slots, of a common cleaning means adapted to wipe material from the upper end of the drum portion downwardly to the disc portion and then outwardly to the periphery of the disc portion where it is discharged. This 10 cleaning means may rotate with the screen, be removed from the disc portion and the drum portion at the same time, and be shifted rearwardly to be placed in engagement with another portion of the screen.

15 Other features of the invention relate to synchronizing the rotary screen and the cleaning mechanism, and to throwing the cleaning mechanism out of operation as it is withdrawn from the rotary screen, and into operation as it is returned to cooperative relation with the screen.

20 Further features and advantages will appear upon consideration of the following description and of the drawings in which

Fig. 1 is a side elevation of the screen, the 25 cleaning means and the operating means whereby both are operated, the casing and supports being shown in section;

Fig. 2 is a fragmentary view of a connection 30 shown in section at the upper part of Fig. 4;

Fig. 3 is a top plan view of the mechanism shown in Fig. 1, parts being broken away to show underlying structure;

Fig. 4 is a longitudinal vertical section on a 35 larger scale, of the structure shown in Fig. 1;

Fig. 5 is a fragmentary top plan view illustrating the manner in which the screenings are discharged from the disc screen;

Fig. 6 is a fragmentary view, partly in section, 40 illustrating the means whereby the cleaning device is withdrawn from the rotary screen, swung rearwardly and returned into engagement with the screen;

Fig. 7 is a section taken along the line 7—7 of 45 Fig. 6; and

Fig. 8 is a section of one of the disc screen sections taken in a plane perpendicular to the screening slots.

Referring to the drawings, 10 represents a well 50 into which empties an influent channel 11 and from which an effluent channel 12 leads. Extending substantially across the top of the well 10 is a bridge 13, here shown as including two longitudinal I-beams 14 supported above the influent channel on a suitable wall and at the effluent side of the well by another I-beam 15. Toward the influent side of the well 10 the bridge is provided with means for supporting the upper end of a rearwardly inclined screen shaft 16, of 55

which the lower end is supported in a suitable manner in the well 10.

As illustrated, in Fig. 1, the upper end of the shaft 16 is mounted in a bearing 17 supported by two I-beams 18 connecting the longitudinal beams 14, and the lower end of the shaft 16 is mounted in a bearing 19 secured between the two inclined I-beams 20. Also the bearing 19 and the corresponding ends of the beams 20 are supported on a wedge-shaped member or casting 21 which in turn rests upon a base 22 projecting upwardly from the bottom of the well, and the other or raised ends of the I-beams 20 rest on a concrete support extending across the effluent channel 12.

Rotatably mounted on the inclined shaft 16 is a rotary screen 23, here shown as including a disc or disc portion 24 and a central drum portion or cone 25 projecting upwardly from the disc portion. If a central drum portion be used, the effective part of the disc portion is in the general form of a flat perforated ring of considerable width which may be made up of a plurality of sections or plates 26 arranged as shown on Fig. 2. Preferably, for the purposes of the present invention, these sections or plates are provided with radial or substantially radial slots 27, the central slots of the sections being radial and the slots at the sides of the central slots departing farther from a strictly radial direction as the sides of the sections 26 are approached.

According to the illustrated embodiment of the invention the disc portion of the screen is supported by a frame comprising a peripheral ring 28 (Figs. 1 and 4) of channel form supported on the outer ends of radial members 29 in the form of I-beams secured at their inner ends to flanges on a tubular hub 30. Support for the inner ends or edges of the screen sections 26 is obtained by means including members 30 connecting the radial beams 29. To assist in supporting the radial members 29, use may be made of suitable tension members 31 connected at their lower ends to the members 29 and at their upper ends to the hub 30. The inner surface of the hub 30 is spaced from the shaft 16 and the lower end of the hub is rotatably mounted on the shaft by means of a bearing sleeve 32 screwed into the lower end of the hub and mounted on a collar 33 secured on the shaft 16 and having a flange 34 overlying the top of the sleeve 32.

Near its upper end the hub 30 is reduced in diameter thereby providing a downwardly facing shoulder 35 at its interior and an upwardly facing shoulder 36 at its exterior. Extending into the reduced upper end of the hub 30 is a sleeve 37 of which the lower edge is flush with the shoulder 35 and is so positioned by means of a flange at the upper end of sleeve 37 fitting into the recessed upper end of the reduced portion of the hub. Support of the hub 30 on the shaft 16 may be obtained by suitable means including a ball bearing of which the lower race is provided by a ring or collar 38 surrounding the shaft 16 and supported by an upwardly facing shoulder on the shaft, and the upper race is provided by a ring 39 engaging the shoulder 35 of the hub and the lower edge of the sleeve 37. Passage of the sewage to be screened, around the lower part of the screen, may be prevented by means of a member 39a connected with the casing of the well and having a circular edge co-operating closely with the circumferential edge 75 of the disc screen which may be supported by

rollers 39b suitably mounted on the wall of the well 10.

Rotation of the rotary screen 23 may be effected by means including a toothed driving ring 40 secured to peripheral ring of the frame of the disc portion of the screen, a gear 41 meshing with the driving ring 40 and mounted on the upper end of a stub shaft journaled in a bracket 42 secured to the I-beams 20, a bevel gear 43 at the lower end of the stub shaft and meshing with a bevel gear 44 on a horizontal shaft 45, a second bevel gear 45a on said shaft 45 meshing with a bevel gear 46 on an upwardly extending shaft 47, a worm gear 48 on the shaft 47 and meshing with a suitable member 49 on a horizontal shaft 50 driven by motor 51 on said bridge 13.

The drum portion 25 of the rotary screen is preferably in the form of a frustum of a cone and is formed at its periphery of a plurality of screen sections 52 having slots extending longitudinally thereof, that is upwardly and downwardly. These screen sections may be connected by bolting them to members 53 which are attached at their lower ends to a ring 54 mounted on the disc frame above the member or members 30 to which they are secured. The top of the drum portion is formed of a plurality of sections 55 of sheet metal engaging the hub 30 and having outer flanged edges extending over the upper edges of the screen sections 52.

An important part of the invention resides in the formation of the rotary screen with screening slots arranged as hereinbefore described and in the provision of cleaning means whereby the screenings will be wiped or brushed longitudinally of the spots and discharged from the periphery of the screen. Preferably the cleaning operation is effected in the following manner:

Provision is made of a brush carrying frame 40 having two vertically arranged sides 56 pivoted at their inner ends on hubs 57 projecting from opposite sides of an annular member 58 rotatably mounted on the shaft 16 by means of ball bearings 59, the annular member 58 being supported against downward movement on the shaft 16 by means of suitable thrust bearings 59a in the form of ball bearings interposed between the member 58 and the upper end of the sleeve 37 at the upper end of the hub 30. Preferably both sets of screen sections are cleaned by the same means which includes a set of rotary brushes 60 fixed on shafts 61 mounted at opposite ends in endless chains 62 and provided at the outer sides of said chains with gears 63 meshing with teeth on continuous racks 64 which also serve as tracks to determine the path of movement of the shafts of the brushes, the lower stretches of the chains 62 being supported by suitable sprockets 64a.

From the showing in Figs. 1 and 3, it will be evident that the brushes are so guided in their movement as to brush down along the drum portion and then outwardly along the disc portion to carry the screenings from the disc portion along the upper face of a discharge platform 64b to a discharge chute 65 from which they may pass to a suitable container 66 for disposal.

It will be evident that if the chains 62 be driven in the required direction, the brushes will be rotated to advance the material in the same direction that the chains move but at a faster rate. To effect this driving of the chains 62 provision is made of a driving shaft 67 located

wires 120 and provided with wire-receiving recesses in which the wires fit, the recesses being open at the top but extending above the middle thereof so that the material at the sides of the recesses overlies the sides of the wires and keeps them from being lifted therefrom. Also the inner end of the frame of the screen section is provided with corresponding recesses extending only part way from the inner edge of the end toward the outer edge thereof which is adjacent to the cone 25, thus limiting the movement of the wires in this direction. The outer end of the section is provided with recesses of the same sort extending completely across the same, so that the wires 120 10 may be inserted longitudinally through these recesses and the recesses in the members 121 until stopped by engagement with the ends of these recesses. After insertion in this way, the wires may be secured against withdrawal, as by placing a member 122 across the outer ends of the recesses in the outer end of the screen section. The sections of the drum portion 25 are formed in substantially the same manner but are curved instead of lying in the same general plane.

25 Recapitulating briefly, the operation of the apparatus is substantially as follows: The liquid from the influent channel 11 passes through the lower part of the disc screen and the larger solids are deposited on the screen. It will be evident 30 that the liquid of the sewage will be held back to such an extent by the screen and the accumulation of solids thereon that the level in the influent channel will be substantially higher than in the effluent channel.

35 With the illustrated arrangement of parts, the screen is turned relatively slowly in a counter-clockwise direction (Fig. 3) and the solids thereon gradually raised above the surface of the sewage at the influent side of the screen. Assuming that the wheels 112 have just been 40 dropped through the openings normally closed by the latch 114, the brush frame will be carried with the screen and the brushes 60 will travel along and clean the screening slots in a path extending from the top of the cone to the inner edge of the screening portion of the disc and then outwardly to the edge of the disc and out over the support or trough 64 to the chute 65 for discharge into a container 66. At the beginning 45 of this brushing action the solids will be deposited on one side (Fig. 5) of the support 64b, and at the end of this brushing action the solids will be deposited on the other side of the support. It should be understood that the timing is such 50 that the brushes starting at the top of the cone when the brush device is thrown into operation will have passed off the disc screen before the brush device is withdrawn from the screen.

55 At the time the wheels 112 drop through the openings controlled by the latch 114 which permits downward movement but prevents upward movement, the toothed member 83 is brought into mesh with the toothed ring 82 thus locking the brush frame to the hub 30 of the screen and causing 60 the brush frame to travel with the screen; and the bevel gear 77 is brought into mesh with the toothed ring 78, thus throwing the brushes into operation. Then as the screen advances it lifts the counterweight 109 from the stop 111 and 65 continues to lift it until the wheels 112 reach the openings 113 and the counterweight 109 lifts the brush frame, thereby breaking the connection which causes the brush frame to rotate with the screen and also breaking the connection 70 through which the motor 51 actuates the brushes.

The counterweight then moves the brush frame rearwardly until the stop 111 is engaged by the counterweight. Although the movement of the counterweight is thus stopped, the momentum of the brush frame at that time is sufficient to carry it along to the spring latch 114 where it is allowed to drop due to the slack formed in the cable 106 after the stoppage of the downward movement of the counterweight. It will be evident that these steps will be repeated in the same sequence 10 as long as the motor 51 is kept at work.

It should be understood that various changes may be made in the construction and arrangement of parts and that certain features may be used without others without departing from the 15 true spirit and scope of the invention.

Having thus described my invention, I claim:

1. In an apparatus of the class described, a disc screen rotated about an inclined axis and having screening slots radially arranged, cleaning means for said disc acting radially and outwardly thereon, and means whereby relative rotation of the cleaning means and screen will be prevented during the cleaning of one radial path and then effected to enable the cleaning means 25 to clean another radial path on the screen.

2. In apparatus of the class described, a disc screen with radial screening slots rotating about an inclined axis, cleaning means for said disc acting radially and outwardly, and means 30 whereby the cleaning means will move with the disc until one radial path on the disc has been cleaned and then will be returned to its starting position to clean a following radial path.

3. In apparatus of the class described, a disc 35 screen with radial slots rotating about an inclined axis, disc-cleaning means, and means whereby the disc cleaning means will act radially and outwardly on said disc and will rotate with said disc until one radial path has been completely cleaned. 40

4. In an apparatus of the class described, a rotary screen including a barrel portion provided with longitudinal screening slots, and means for cleaning said barrel portion in successive longitudinal paths including means to act along the 45 entire length of said slots, and means whereby the cleaning means will turn with said barrel during the cleaning action along one of said paths.

5. A rotary screen comprising a disc portion 50 and a central drum portion having longitudinal screening slots extending substantially from end to end of said drum portion to facilitate cleaning by means acting from end to end of said drum portion, and wiping means acting to wipe 55 along the longitudinal screening slots of said drum portion and across the disc portion of the screen to discharge screenings at the periphery of the disc.

6. A rotary screen comprising a central barrel 60 having longitudinal screening slots and a disc surrounding one end of said barrel and formed of sectors each of which has a central radial screening slot and slots parallel thereto at opposite sides thereof, and means to move the screenings along said longitudinal slots in the central barrel and along the slots in the disc portion to discharge the screenings at the periphery of the disc portion. 65

7. In an apparatus of the class described, a 70 rotary screen comprising a disc portion having substantially radial screening slots and a central drum portion having longitudinal screening slots, and brushing means acting to brush along said longitudinal slots and outwardly along said radial 75

slots to discharge the screenings at the periphery of the disc.

8. In an apparatus of the class described, a rotary screen having its axis of rotation inclined with respect to the vertical and comprising a disc portion having substantially radial screening slots and a central drum portion having longitudinal screening slots, a discharge platform arranged to receive screenings from the rim of the disc portion, and brushing means acting to brush downwardly along said longitudinal slots and outwardly along said radial slots and over said platform.

9. The combination with a rotary screen comprising a disc portion having substantially radial screening slots and a central cone portion having longitudinal slots, means for rotating the screen, screen-cleaning means including brushes for brushing the screenings downwardly along the longitudinal slots of the cone and outwardly along said slots in the disc, a brush-carrying frame mounted to swing about the axis of said screen and to be separated from the screen or moved into cooperative relation therewith, means whereby said frame will be caused to turn with said screen when in cooperative relation therewith for cleaning purposes and will be freed when separated from the screen, means whereby the brushes will be actuated when the frame is down and will be at rest when the frame is raised, a traveling carriage connected with said frame to travel therewith but to permit vertical movement of the frame with respect thereto, a pulley on said carriage, a vertically movable counterweight to the rear of the frame when referred to the direction of rotation of the screen, a pulley above said counterweight, a flexible connector attached to said counterweight and to said frame and extending over said pulleys, and means for controlling the action of the counterweight on the frame including means to hold the frame down to travel with the screen and then, after releasing the same to permit the counterweight to lift a frame and start it rearwardly, to hold the frame in raised position until after the counterweight is stopped in its downward movement and slack is formed in the flexible connector to permit the frame to drop, and a spring catch permitting such dropping of the frame but preventing upward movement thereof.

10. The combination with a rotary screen comprising a disc having substantially radial screening slots and a central drum having longitudinal slots, means for rotating the screen, screen-cleaning means including brushes for brushing the screenings downwardly along the longitudinal slots of the drum and outwardly along said slots in the disc, a brush-carrying frame mounted to swing about the axis of said screen and to be separated from the screen or moved into cooperative relation therewith, means whereby said frame will be caused to turn with said screen when in cooperative relation therewith for cleaning purposes and will be freed when separated from the screen, and means for moving the brush-carrying frame into cooperative relation with the screen, holding the frame in such relation to the screen while the screen rotates through a predetermined angle, withdrawing the frame from the screen, and swinging the frame rearwardly preparatory

to again moving it into cooperative relation with the screen.

11. The combination with a rotary screen comprising a disc having substantially radial screening slots and a central drum having longitudinal slots, means for rotating the screen, screen-cleaning means including brushes for brushing the screenings downwardly along the longitudinal slots of the drum and outwardly along said slots in the disc, a brush-carrying frame mounted to swing about the axis of said screen and to be separated from the screen or moved into cooperative relation therewith, and means causing the brushes to effect complete cleaning along successive longitudinal paths on the drum and corresponding successive radial paths on the disc, said last mentioned means including means whereby the frame will be caused to turn with said screen while in cooperative relation therewith for cleaning purposes and will be freed upon separation from the screen. 5 10 15 20

12. The combination with a rotary screen comprising a disc portion having substantially radial screening slots and a central cone portion having longitudinal slots, means for rotating the screen, screen-cleaning means including brushes for brushing the screenings downwardly along the longitudinal slots of the cone and outwardly along said slots in the disc, a brush-carrying frame mounted to swing about the axis of said screen and to be separated from the screen or moved into cooperative relation therewith, and means effecting complete cleaning by the brushes along successive longitudinal paths on the drum and corresponding radial paths on the disc, said last mentioned means including means whereby the brushes will be actuated when the frame is down and will be at rest when the frame is raised. 25 30 35

13. The combination with a rotary screen comprising a disc having substantially radial screening slots and a central drum having longitudinal slots, means for rotating the screen, screen-cleaning means including brushes for brushing the screenings downwardly along the longitudinal slots of the drum and outwardly along said slots in the disc, a brush-carrying frame mounted to swing about the axis of said screen and to be separated from the screen or moved into cooperative relation therewith, means whereby said frame will be caused to turn with said screen when in cooperative relation therewith for cleaning purposes and will be freed when separated from the screen, a traveling carriage connected with said frame to travel therewith while permitting vertical movement of the frame with respect thereto, a pulley on said carriage, a vertically movable counterweight to the rear of the frame when referred to the direction of movement of the screen, a pulley above said counterweight, a flexible connector attached to said counterweight and to said frame and extending over said pulleys, and means for controlling the action of the counterweight on the frame including means to hold the frame down to travel with the screen and then, after releasing the frame to permit the counterweight to lift it and start it rearwardly and to hold the frame in raised position until after the counterweight is stopped in its downward movement and slack is formed in the flexible connector to permit the frame to drop.

JOHN B. GOLDSBOROUGH
